UNITED STATES PATENT OFFICE.

JOHN GILBERT, OF NEWARK, NEW JERSEY.

IMPROVEMENT IN DIES FOR CAN-SPOUTS.

Specification forming part of Letters Patent No. **179,295**, dated June 27, 1876; application filed May 22, 1876.

To all whom it may concern:

Be it known that I, JOHN GILBERT, of Newark, in the county of Essex and State of New Jersey, have invented a new and useful Improvement in Dies for Forming Can-Spouts, of which the following is a specification:

Figure 1 is a plan view of the blank from which a spout is to be formed. Fig. 2 is a face view of the lower die for bending the blank. Fig. 3 is a vertical longitudinal section of the same, taken through the line *x x*, Fig. 2, and showing the upper die in side view. Fig. 4 is a vertical cross-section of the same, taken through the line *y y*, Fig. 3. Fig. 5 is a perspective view of the blank after the first operation. Fig. 6 is a cross-section of the same, taken through the line *z z*, Fig. 5. Fig. 7 is a side view, partly in section, of the dies and former for bringing the spout into tubular form and overlapping its edges. Fig. 8 is a cross-section of the same, taken through the line *w w*, Fig. 7. Fig. 9 is the same section as Fig. 8, but showing the forming-die replaced by the finishing-die. Fig. 10 is a cross-section of the spout as it comes from the forming-die. Fig. 11 is a cross-section of the same as it comes from the finishing-die. Fig. 12 is a perspective view of the completed spout.

Similar letters of reference indicate corresponding parts.

The object of this invention is to furnish dies for forming curved spouts for oil-cans and other uses, which will enable the said spouts to be formed rapidly, accurately, and neatly, and at much less expense than when formed in the usual way.

The invention will first be described in connection with drawing, and then pointed out in the claim.

Curved spouts have heretofore been made by making a straight spout, running it full of lead, bending it into the desired form, melting out the lead, and afterward retinning the spouts. This mode of construction is tedious, and makes the spouts expensive.

I will describe my improved dies in connection with the operation of forming a spout.

A represents the blank out of which a spout is to be formed, and which is cut out of sheet metal into the required shape and size.

The blank A is laid upon the face of the die B, and is brought into the exact position by guide-pins *b*', attached to the face of the said die. The die B has a slot, *b*², formed through it, through which the blank A is forced by the flange *c*' of the upper die C. The face or edge of the flange *c*' is concaved, as shown in Figs. 3 and 4, so that the blank A¹, when it comes from the dies B C, may be in the form of a curved half-tube, as shown in Figs. 3 and 4. The blank A¹ is then put upon a former, D, of the exact size and shape of the required spout, and which is provided with a handle, *d*', and is pivoted to the end part of the die E. In the face of the die E is formed a groove, *e*', which is curved into the exact form of the concaved side of the required spout, into which the former D and blank A¹ are lowered, and in which the said blank is operated upon by the die F. In the face of the die F is formed a groove, *f*', which is curved into the exact form of the convex side of the required spout. In the bottom of the groove *f*' is formed a shoulder of a height equal to the thickness of the plate of which the spout is being formed. As the die F is forced downward it presses the edges of the blank A¹ inward until one edge strikes the shoulder of the groove *f*', and the other edge slips past and underlaps it, thus forming the blank A². The die F is then removed, and the die G is forced down upon the blank A² while still upon the former D, and in the groove *e*' of the die E. The die G is made with a groove, *g*', like that of the die F, except that it has no shoulder, and closes the overlapped edges of the blank A² down upon each other, forming the spout A³, which only required to be soldered to form a finished spout.

Having thus described my invention, I claim as new and desire to secure by Letters Patent—

The combination of the series of dies B C E F G with the former D, the die-faces having a longitudinal curve corresponding to that of the former, substantially as and for the purpose specified.

JOHN GILBERT.
